UNITED STATES PATENT OFFICE.

MICHELE LIPPIELLO, OF UNIONTOWN, PENNSYLVANIA.

SHOE-UPPER.

1,127,037.

Specification of Letters Patent.

Patented Feb. 2, 1915.

Application filed July 2, 1912. Serial No. 707,306.

To all whom it may concern:

Be it known that I, MICHELE LIPPIELLO, a citizen of the United States, residing at Uniontown, in the county of Fayette and 5 State of Pennsylvania, have invented new and useful Improvements in Shoe-Uppers, of which the following is a specification.

This invention relates to shoe uppers and the principal object of the invention is to 10 provide a shoe upper which is constructed of a single piece of leather and joined together in such a manner that practically no seams are necessary.

A further object of the invention is to 15 provide a shoe in which the upper is constructed of a single piece of material, whereby the lasting and stitching operation are rendered more simple and less expensive.

Further objects of this invention will appear as the following specific description is 20 read in connection with the accompanying drawing, which forms a part of this application, and in which:—

Figure 1 is a side elevation of the completed shoe. Fig. 2 is a plan view of the 25 blank used in forming the upper.

In producing the shoe, the upper is constructed of a single piece of material comprising a vamp 1, foxing 2, and top 3, all of 30 which are formed from an integral piece of leather, the foxing and vamp being joined together upon one side of the shoe by a seam 3^a which forms an angular continuation of the button or lacing connection 4 which joins 35 the free edges of the upper, as is well understood. In cutting the upper to produce the form shown in Fig. 2, a piece of leather is folded on the line *a*—*a* and then upon the line *b*—*b* and the bottom of the vamp and 40 foxing cut upon a compound curve 5 so as to procure the proper form for attaching the upper to the sole. The portion of the foxing strip which is in the rear of the line *a*—*a* on the blank is cut inwardly on an obtuse angle 45 to the bottom line of the blank, as shown at

6, then outwardly at right angles, as shown at 7, and again at right angles to the cut 7, so as to produce the tongue 8 which is preferably stitched to the under side of the vamp so as to prevent tearing of the leather when 50 the lacing or button connection is open. The opposite side of the vamp is cut inwardly and on an acute angle, as shown at 9, and then on a compound curve 10 to produce an artistic edge for the overlapping portion of 55 the top in which the bottom holes 11 are formed. Suitable straps 12 may be produced in cutting the blank, as shown, so as to make a more ornamental structure or the straps 12 may be left entirely off. From 60 the upper end of the tongue 8, the top is cut on a deep inward curve, as shown at 13, so as to conform to the curvature of the wearer's ankle. While the appearance of the blank would naturally lead one to believe 65 that the shoe would be of awkward or roughly finished form, this would not be the case, as when the upper is stretched over the last and properly connected to the sole, the shoe will assume the form shown in Fig. 1 70 and will be free of seams across the instep and at the heel. Also there will be no seams connecting the foxing strip and the top or any means connecting the vamp and the top. 75

What is claimed is:—

A shoe upper having top, vamp and foxing portions, the vamp portion having a straight edge, the foxing portion having a straight edge, said straight edges meeting and being secured together by a seam, the 80 top portion having an extension which projects under the vamp portion above the said meeting edges and extends from said seam toward the toe of the shoe.

In testimony whereof I affix my signature 85 in presence of two witnesses.

MICHELE LIPPIELLO.
